Design No. 150

FIG. 1.

Enoch Woolman's Door, n. s. or. strap Hinges. —

Patented Dec. 11, 1851.

FIG. 3.

Enoch Woolman
Door Hinges.Enoch Woolman
Door Hinges.

Enoch Woolman of Damascusville, Ohio.

Letter Patent No. 750. Dated December 11, 1833.

File. 150

My Schedule referred to in these Letters Patent and making part of the same.

To all whom it may concern,

Be it known, that I, Enoch Woolman of Damascusville, Columbiana County, State of Ohio, have invented or produced a new and original design for a strap hinge to be made of malleable cast iron, and I do hereby declare that the following is a full and exact description of the same, reference being had to the accompanying drawing and to the letters of reference marked thereon.

My design consists in arranging on both divisions of a strap hinge straight & annular ribs which serve the double purpose of ornamenting the exterior of the same and rendering them stronger and better adapted for resisting the strain exerted by the door to which they are fastened.

In reference to the drawing which forms a part of this specification,

Fig. 1, is a front view of both divisions of a strap hinge with my improved design of straight and annular ribs.

Fig. 2, an edge view of the division of the hinge secured to the door.

Fig. 3, an edge view of the division of the hinge secured to the post.

The strap of the division A, of the hinge secured to the door, is of the usual length & form used for such purposes; on the outside however, I cast a rib a, terminating at one end at the joint b, and at the other end in the annular rib C, and intersected near the joint by a square raised portion d, & near the middle by another annular rib e, the square and annular ribs having countersunk orifices through which pass the screws for securing the strap to the door. On the other division B, of the hinge which is secured to the post I cast a curved rib f, extending from the joint to an annular rib g, and near the joint and on each side of the curved rib f, I place two other annular ribs h, through these as well as through the annular rib g, pass the screws for securing this division of the hinge to the post. I claim the design for strap hinges to be made of malleable cast iron ornamented by the straight, curved, and annular ribs substantially in the manner set forth

Ex: 103.
